(57) **CLAIM**

The ornamental design for a feed wheel as shown and described.

DESCRIPTION

FIG. 1 is a top perspective view of a feed wheel, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a cross-sectional view thereof, taken along line 6-6 as shown in FIG. 5; and,

FIG. 7 is a bottom perspective view thereof.

The right side elevational view and the left side elevational view are substantially the same as the front elevational view and the rear elevational view. The broken lines shown in the Figures are environment only and show portions of the feed wheel that form no part of the claimed design. The broken lines immediately adjacent the shaded areas represent the bounds of the claimed design while all other broken lines are directed to environment and are for illustrative purposes only; the broken lines form no part of the claimed design.
